UNITED STATES PATENT OFFICE

THOMAS M. DELIGIANES AND ANDREAS A. BOURDES, OF CHICAGO, ILLINOIS

SERVICE APPARATUS

Application filed July 20, 1928. Serial No. 294,255.

This invention relates to certain novel improvements in service apparatuses, and has for its principal object the provision of an improved construction of this character which will be highly efficient in use and economical in manufacture.

The salient object of our invention is to provide a service apparatus which will be particularly adapted for use in connection with lunch counters and the like and consists in providing a carriage which will be movable along the counter on which various appurtenances for the service of patrons will be provided, as for example, containers for napkins and sugar, and condiments such as salt and pepper.

An object of the invention, ancillary to the foregoing, is to provide novel means of supporting the carriage for movement.

A still further object of the invention is to arrange the carriage in a manner such that the holders for the various appurtenances will be arranged in a manner such that the appurtenances may be readily removed.

Other and further objects will appear hereinafter.

The invention consists in the novel combination and arrangement of parts to be hereinafter described and claimed.

The invention will be best understood by reference to the accompanying drawings, wherein a preferred form of construction is shown, and in which:

Fig. 1 is a front elevational view, in which certain parts are broken away, depicting a preferred form of construction for our improved device in association with a so-called lunch counter;

Fig. 2 is a plan view, in which certain parts are broken away, of the device illustrated in Fig. 1;

Fig. 3 is a transverse sectional view taken substantially on the line 3—3 on Fig. 2;

Fig. 4 is a fragmental detail view depicting the manner in which one of the appurtenances is supported on the carriage; and

Fig. 5 is a fragmental detail view of the mechanisms employed for supporting the carriage for movement relative to the counter.

At lunch counters, and similar places of

eating, it is customary to provide at various intervals dispensers holding napkins, sugar, and condiments. These holders are usually arranged at definite intervals and are intended to be disposed such that all patrons will have access to one of the holders. However, this requires a plurality of holders, and it sometimes occurs that patrons are unable to reach the holder without disturbing the other patrons. It is also customary to provide a dispenser for sugar and the like which is open and obviously, this is not sanitary nor conducive to good service.

It is therefore an object of our invention to provide a service holder which may be moved along the counter and which will have containers thereon that will house the various appurtenances in such a manner that the materials such as sugar and condiments, as well as napkins, may be maintained in a sanitary condition. Mechanisms for accomplishing this purpose are disclosed in the accompanying drawings, wherein 10 indicates the main body portion of the housing which is preferably substantially L-shaped in formation so as to embody a horizontally extending portion 11, and a vertically extending portion 12. Associated with the substantially L-shaped portion 10 is a portion 11 which includes a front rail 13 and end constructions 14 and 15. The carriage thus defined is preferably supported for movement along the counter and obviously, this can be attained in various manners, without departing from the purview of our invention. However, in the embodiment of our invention illustrated, we provide on the under side of the portion 11, adjacent the front rail 13, a plurality of bearing constructions 16, in which rollers 17 are rotatably mounted. These rollers 17 are preferably tired with a suitable noiseless material such as, for example, rubber. To the rear end of the plate 11 we secure a bracket member 18, which includes a downwardly depending portion 19. A substantially U-shaped member 20 is provided, and the limp portions 21 thereof are arranged in abutting relation with respect to the surface of the portion 19, such that the bight-portion 22 is disposed in spaced rela-

tion with the face of the member 19 so as to provide a space therebetween. This space is indicated by 23 in the drawings, and rotatably mounted in this space 23 is a roller 24 which is mounted on the axle 25 that serves to hold the members 20 and 19 together, although it is to be understood that these members might be joined in any desired manner. Extended through the space 23 below the roller 24, is a track 26, which is preferably formed from rectangular stock and made from a hardened material. The end portions of this track 26 are preferably secured to the lunch counter 27 in any approved manner, as by the securing elements 28 (Fig. 1). The track 26 is substantially equal to the width of the space 23 and therefore, the carriage is supported such that transverse movement thereof is prevented, the rollers 17 and 23 supporting the device such that it may be moved only longitudinally of the counter.

Suitably supported from the portion 11, adjacent the end portions 14 and 15, are substantially U-shaped bracket members 29 which include limb portions 30 and 31 and a bight-portion 32. The bight-portion 32 is preferably secured to the portion 11 in any approved manner as by the rivets 33. Extending upwardly from the bight-portion 32 and disposed between the end portions 30 and 31, are tab portions such as 34. The tab portions 34 are preferably shorter than the end portions 30 and 31. Struck inwardly from the portions 30 and 31 in spaced relation with respect to the bight-portion 32, are lugs 35. The members 29 thus formed are adaptable to support suitable containers which in the present instance are indicated by 36. These containers 36 may be of the open end variety, such as depicted, or they may be closed housings having suitable openings formed therein, and they are intended to house napkins or similar articles. It is apparent that by mounting the containers 36 in the members 29 that these containers 36 may be readily removed so as to facilitate the cleaning or refilling thereof. Arranged intermediate the housings 29 and adapted to extend upwardly from the portion 11 are bracket members 37. The bracket members 37 include foot portions 38 that are secured to the portion 11 through the medium of suitable securing devices such as the rivets 39. At the upper ends of the brackets 37 pad portions 40 are secured. These brackets 37 are intended to support suitable supporting members which are adapted to carry a dispenser for sugar or the like.

A second dispenser is generically indicated by 41 in the drawings, and is intended to be substantially similar to the sugar dispenser described and claimed in our co-pending application, Serial Number 366,362, filed in the United States Patent Office on or about May 27, 1929. This second dispenser includes an

intermediate portion 42 and has end constructions 43 and 44 associated therewith. Associated with the end construction 44 is a follower construction 45 which has a discharge opening provided at the apex thereof. Carried by the end construction 44 is a cylindrical member 46 which has openings 47 provided therein. Discharge through the opening 47 is controlled by a plunger 48 which is operated by a pin member 49 that is adapted to have a portion extended out through the opening 47. By positioning a spoon or the like below the pin member 49, the same may be raised to elevate the plunger 48 and thus permit passage through the openings 47 whereby the material such as sugar contained in the housing defined will be permitted to dispense through the opening 47. The container 41 is filled by removing the end construction 43 which preferably carries an agitating arrangement generically indicated by 50 in the drawings, that is operated from the handle 51 arranged externally, of the housing.

Secured to the pads 40 are the foot portions 52 of the supporting bands 53. The supporting bands 53 include portions 54 adjacent the foot portions 52 which are adapted to be arranged parallel to each other and suitable substantially U-shaped clips 55 are adapted to be fitted over these parallel portions 54 so as to secure the same together. The intermediate portions of the strips 53 are substantially semi-circular in outline and include substantially vertically extending portions 56 which are adapted to embrace the sides of the container 41 and the lower edges of these vertical portions 56 terminate in serrated portions 57 that are angled inwardly so as to embrace the outer surface of the end portion 44. In this manner the container 41 is supported from the brackets 37 and by removing the clips 55, the same may be readily removed so as to facilitate the cleaning thereof.

Adjacent the front rail 13 in front of the brackets 37 suitable condiment holders may be mounted and in the other space of the device any other desired appurtenances may be mounted.

It is apparent from the foregoing description that we have provided a construction which may be moved relative to a counter or the like and this construction is arranged such that the various portions thereof adapted to contain service items may be readily removed so as to facilitate the cleaning and refilling thereof.

It is apparent that one of these devices may be used to serve a number of customers inasmuch as it may be moved along the counter and therefore, the number of holders employed may be greatly reduced over the usual number of stationary holders required.

While we have illustrated and described the preferred form of construction for car-

rying our invention into effect, this is capable of variations and modifications, without departing from the spirit of the invention. We, therefore, do not wish to be limited to the precise details of construction set forth, but desire to avail ourselves of such variations and modifications as come within the scope of the appended claims.

Having thus described the invention, what we claim as new and desire to protect by Letters Patent is:

1. A service apparatus for restaurant counters and the like, comprising a carriage, means for supporting said carriage for movement over the surface of a counter, said means including rollers mounted on the under side of said carriage adjacent one edge thereof adapted to engage the upper face of said counter, and including portions depending below said counter at one end thereof, a rail member disposed below the upper surface of said counter, said portions engaging said rail member, and guiding members secured to said depending portions for movement along said rail member.

2. A service apparatus for restaurant counters and the like, comprising a carriage member, roller members mounted adjacent the forward edge of said carriage, a bracket member depending from the rear edge of said carriage, said bracket member having a passage formed therein through which a track member may be extended below the upper surface of said counter, and rollers mounted in said passages adapted to engage said track.

3. In combination with a service apparatus for restaurant counters and the like including a carriage, a bracket member depending from said carriage below the upper surface of said counter and having a substantially rectangular passage formed therein, a track member adapted to be extended through the lower portion of said substantially rectangular portion and being adapted to be of a width substantially equal to the width of said passage, and a roller member mounted in said passage adjacent the upper edge thereof adapted to travel along said track.

4. A service apparatus for restaurant counters and the like, comprising a carriage, means for supporting said carriage for movement over the surface of a counter, said means including rollers mounted on the under side of said carriage adjacent one edge thereof adapted to engage the upper face of said counter, and including portions depending below said counter at one end thereof, a rail member disposed below the upper surface of said counter, said portions engaging said rail member, guiding member secured to said depending portions for movement along said rail member, said guiding members including substantially U-shaped brackets, means for securing said brackets to said depending

portions, and rotatable members on said last named means for movement over said rail.

In testimony whereof we affix our signatures.

THOMAS N. DELIGIANES.
ANDREAS A. BOURDES.
